UNITED STATES PATENT OFFICE.

ALBERT W. MARSHALL, OF INDIANAPOLIS, INDIANA, ASSIGNOR TO THE AMERICAN PRESS ASSOCIATION, OF CHICAGO, ILLINOIS.

ELECTROTYPE-PLATE AND HOLDER.

SPECIFICATION forming part of Letters Patent No. 312,569, dated February 17, 1885.

Application filed January 12, 1884. (Model.)

To all whom it may concern:

Be it known that I, ALBERT W. MARSHALL, a citizen of the United States, residing in the city of Indianapolis, county of Marion, and 5 State of Indiana, have invented a new and useful Improvement in Electrotype-Plates and the Mode of Securing them in the Forms for Printing, of which the following is a full, clear, and exact description, such as will enable others skilled in the art to which it 10 pertains to make and use the same.

The object of my invention is especially to improve the means by which newspapers at a 15 distance are furnished printing-matter from a central office in the form of stereotype-plates; and it consists in substituting for such plates an electro-shell made of flexible material without the heavy metal backing now in general use, and in providing such shell with 20 edges extending out beyond the line of the printing-surface to form flanges, whereby the shell may be adapted to a block for the purposes of printing. The shell is formed by an electric deposition of copper or other metal. 25 When made of copper, it is formed in a battery on a wax mold, in the manner followed in making an ordinary electroplate, by which a fac-simile of the type-form is produced. A margin or edge is allowed to form on two or 30 more of the edges of this plate, as and for the purpose now to be described.

In the accompanying drawings I have shown ways of securing this shell to a block or base.

Figure 1 represents a section of the shell 35 as used in the columns of a newspaper. *a a* are the flanges for the purpose of holding it in the forms. These flanges, of the same material and cast integral with the shell, are turned at right angles with the printing-surface 40 face of the shell, as shown in Fig. 2. It is designed that the shell be mounted on a base of wood or metal to make it type-high.

Fig. 3 represents a section of shell adjusted to a movable base, ready for use. The flanges 45 *a a* lap down on the sides of the base *C*, which has a plain upper surface, and the column-rule *D* in Fig. 3 presses against the flange when the forms are "locked up," thus holding the shell firmly on the base *C*, as will be 50 readily seen by any one skilled in making up forms for printing. It is evident that the

flanges are adapted, by reason of their flexibility, to be secured to the block in other ways than here shown. In making electrotypes of wood-cuts and other work it is desirable to 55 have the flange above referred to on foursides of the printing-surface of the "shell," and, as shown in Fig. 4, these flanges can be made secure to a wood or metal base, by screws or 60 nails, for the purpose set forth.

Fig. 5 represents a dash used in the columns of a newspaper, and provided with flanges at each end to secure it to a base, in a similar manner as the section of shell shown in Fig. 3. Fig. 6 is a bottom perspective view of the 65 electrotype-shell, and Fig. 7 an enlarged section of the same.

In the process of casting the shell the electro-deposit may be allowed to thicken to a greater extent than is necessary when "backing" is to be employed, or the shell may be very slightly backed; but in either case not to a thickness inconsistent with its perfect pliability, or with the advantages to be accomplished by the use of the shell, as will now be 75 stated.

One of the most important advantages of my improvement lies in the fact that by reason of the thinness and pliability of the plate it can be used with all forms of printing-surfaces, whether straight or curved, without re-adaptation to meet degrees of curvature—an impossibility with stereotype-plates—as, for example, on what are known as "tuttle-presses." Again, an electrotype-shell thus 85 constructed can be cut by a pair of shears into any desired length to adapt the matter to the make-up of the paper, similar to many stereotype-plates now in use, and by reason of its lightness it can be transported cheaply by mail, 90 or if by express or by freight, at greatly-reduced rates, thus saving a very large amount in the cost of transportation. In this connection it may be said that twenty inches of my improved plate ready to be put on the press 95 weighs half an ounce, while the same length of the lightest stereotype fit to use weighs a little less than three pounds.

As to cost of production, the value of metal in a twenty-inch stereotype-plate is about 100 twenty-five cents (25c.) whereas the value of my plate of the same length is less than three

cents. A large proportion, at least twenty-five per cent., of the whole amount of material used in stereotypes is lost annually, whereas such loss in material by employment 5 of this plate is so small as not to be considered.

I am aware that in addition to the electro-shell with a backing, iron or steel coatings of printed surfaces forming patterns for the purpose 10 of printing therefrom are old, and also that, in combination with a double-faced or reversible stereotype-plate, a flexible extension or margin made of sheet metal or analogous material differing from the body of the 15 plate has been employed; but none of these devices accomplish the objects of my invention as herein set forth.

What I claim is—

1. A flexible electrotype-shell without the usual backing, in combination with a base or 20 block having a plain upper surface supporting the shell at the required height for printing therefrom, substantially as described.

2. A shell having edges made of the same material and integral therewith, the said edges 25 extending out beyond the line bounding the printing-surface a suitable distance to form flanges, whereby the shell may be adapted to a block for the purpose of printing therefrom, substantially as described.

ALBERT W. MARSHALL.
